MATRIX

Application filed September 9, 1929. Serial No. 391,325.

Generically this invention relates to matrices but it more especially comprehends the type adapted for use in connection with the production of resilient plates adaptable for fine line or half tone color printing on fabrics such as flour bags and the like.

The principal object of this invention is the provision of a matrix and process of making same comprising a metallic facing sheet susceptible of producing type shoulders and depressions of sufficient height and depth, respectively, on a printing plate to effect sharp contours and accurate register in color and fine line or half-tone printing on relatively coarse fabrics such as flour sacks, said metallic sheet having applied thereto a non-metallic material, the latter having a backing of metallic material, whereby such backing material may be applied at its proper temperature for full fluidity and homogeneous casting without adversely affecting the facing sheet carrying the impression.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a transverse sectional view taken through the type form and the impression sheet in contact therewith;

Fig. 2 is a similar view with the non-metallic or fibrous material applied to the impression sheet;

Fig. 3 is a vertical section through the casting box and components as shown in Fig. 2;

Fig. 4 is a similar view to Fig. 3 after the introduction of the backing material; and

Fig. 5 is a sectional view through the complete matrix.

The types of matrices of this character heretofore in use and the methods of producing same have proven deficient in the production of resilient printing plates for fine line color printing on coarse fabrics for many reasons, certain of said methods being to

place a type form with a lead or other metallic type of impression sheet in contact therewith in a horizontal position and then pouring on top of said sheet, after treatment with a cleansing and fluxing material, an alloy composed of lead and other material having a relatively low melting point, so as to become homogeneous with the sheet carrying the impression. However, experience has demonstrated that casting stereotyped metal in a thin sheet over a form in a horizontal position does not give homogeneous results. And, further, matrices so constructed owing to the difference in melting point between the facing and backing metals effects a sufficient distortion of the impression sheet or facing to affect the sharp contours of the printing plate produced thereby and prevent accurate registry in fine line color printing.

Again, other methods consist in pressing into a type face a soft alloy or foil facing sheet and backing same with a phenolic substance adapted to harden and set under heat and pressure, and the impression surface of such type of matrix, even though employing a low melting point facing sheet, becomes distorted during the molding process in the production of resilient printing plates sufficient to preclude a fine line color register by the resilient printing plate, and consequently, rendering such plate incapable of producing fine line and half tone printing on relatively coarse fabrics; and it was to overcome the deficiencies of such methods, and provide a matrix capable of producing under heat and pressure a resilient printing plate capable of effecting fine line half tone color printing on coarse fabrics such as flour sacks and the like, which I accomplish by my improved method of pressing an alloy sheet having a relatively low melting point into the surface of a type form, applying an adhesive fibrous heat resisting backing sheet to said metallic sheet, and then applying to the fibrous sheet a backing of stereotype metal at its proper temperature for full fluidity and homogenous casting, with the fibrous backing in a vertical position during the backing process, without adversely affecting the sheet carrying the impression.

In the illustrated embodiment characterizing this invention there is shown a matrix A, type form or positive pattern plate B, an alloy facing sheet C, fibrous material sheet D, and metallic backing E, and in carrying out the process of my invention the facing or impression alloy sheet C, the melting point of which is relatively low, is pressed into the face of type form B, and then superimposed on said sheet C is a sheet D of fibrous heat-resisting material such as cartridge paper or other suitable material, and which, though not always necessary, preferably has its contact surface treated with an adhesive substance. Type form B, facing sheet C, and fibrous sheet D, are then placed as a unit in the casting box F in a vertical position, and the stereotype or other metallic material E of a relatively high melting point is poured at its proper temperature for full fluidity into the casting box which is in a vertical position and allowed to rise to a height of several inches above the level of the form B, thereby obtaining a most homogeneous cast with a relatively high melting point backing.

The mass, after the material E has cooled, is then removed from the casting box F and type form B removed, leaving matrix A, and which matrix thus formed, by virtue of its homogeneous backing is capable of withstanding great pressure, and owing to the fibrous sheet interposed between said backing and surface impression sheets is capable of withstanding the heat and pressure incident to the molding process in the production of resilient printing plates, and of imparting to such printing plate sharp type face fine line contours for fine line, half tone, color printing, whereby perfect color registry is effected.

It is apparent that by the above method I have produced a matrix overcoming the inherent deficiencies of those heretofore in use for the production of resilient printing plates for fine line printing on coarse fabrics, some of the advantages of my improved method being apparent from the fact that by interposing the heat resisting material between the impression sheet and backing material I utilize a much higher melting point backing material than has been heretofore possible, without affecting the impression sheet, and which has only been accomplished after great experimentation.

For the purpose above outlined, to successfully unite a molded face sheet with a backing up metal to effect a practically homogeneous matrix proved a most difficult operation to solve, since if the backing metal is at a proper temperature for pouring into a casting box it is so high that it will melt the impression sheet molded on the type matter, and if the backing metal is not at this high temperature it will not flow freely over the molded sheet and will not form a homo-

geneous casting. Through said experimentation it was found that such homogeneous casting could not be obtained by merely floating molten metal on the type form containing the molded impression sheet still in contact with the type matter in a horizontal plane, and was only possible by applying such metal to the fibrous backed surface of the impression sheet when in a vertical plane, and wherein such material was permitted to rise above the level of the form. Otherwise it is not a homogeneous casting unless the metal used for backing is of a very low melting point, and if it is of a low melting point, it naturally is soft and not suitable for molding plates under high pressure, which is essential for the production of resilient printing plates capable of effecting fine line and accurate color registry on coarse fabrics, and which has not been possible of attainment by the types of matrices heretofore in use.

Although in practice I have found that the form of my invention illustrated in the accompanying drawings and referred to in the above description as the preferred embodiment is the most efficient and practical; yet realizing the conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. A printing plate matrix comprising a design bearing impression sheet, a sheet of non-metallic heat-resisting material, and a metallic backing material.

2. A printing plate matrix, comprising a design bearing impression sheet of moldable material, a sheet of fibrous heat-resisting material, and a metallic backing for said fibrous material.

3. A matrix for the production of resilient printing plates, comprising a design bearing impression sheet of moldable material, a metallic backing material of a melting point different from that of the impression sheet, and a sheet of heat-repellant material interposed between the impression and backing materials.

4. A method of producing a printing plate matrix consisting in subjecting a sheet of moldable material to pressure in contact with a type body to form type-forming depressions and non-type-forming elevations, then applying a backing of fibrous heat resisting material to said first mentioned material, and then applying a backing of molten material to the back of the heat-resisting material and permitting said molten material

to harden to form a backing for said heat-resisting and moldable materials.

5. A method of producing a printing plate matrix consisting in forming an impression sheet of moldable material with a design; then treating the surface of a sheet of fibrous heat-resisting material with an adhesive substance, then applying said sheet to the back of said moldable material with the adhesive surface in contact therewith, and then applying a backing to said fibrous sheet of metallic material of a high melting point in a molten state, and permitting said material to harden to form a solid backing for said fibrous and impression sheets.

6. A method of producing a printing plate matrix consisting in forming an impression sheet with a design, then applying a sheet of fibrous heat resisting material to the back of said impression sheet, then placing said type form, impression sheet and fibrous sheet, in a casting box in a vertical position, then pouring into said casting box a metallic material at the proper temperature for full fluidity, and permitting such material to rise to a point above the level of the type form, impression and fibrous sheets, and permitting said metal to harden to form a homogeneous backing for said fibrous and impression sheets.

7. A method of producing a printing plate matrix consisting in subjecting a sheet of moldable alloy of low melting point to pressure in contact with a type body to form type forming depressions and non-type forming elevations in the sheet, then applying a sheet of fibrous heat-resisting material to the back of said alloy sheet, then placing said type form, moldable impression sheet and fibrous sheet, in a casting box in a vertical position, then pouring into said casting box in contact with said fibrous sheet a stereotype metal of high melting point at the proper temperature for full fluidity and allowing said material to rise above the level of said form, impression and fibrous sheets, and permitting such material to cool to form a homogeneous backing for said impression and fibrous sheets without affecting the moldable impression sheet during the last mentioned backing process.

This specification signed this 31st day of July, A. D. 1929.

SAMUEL C. FORRESTER.
